UNITED STATES PATENT OFFICE

2,506,216

SELF-LOCKING CENTRIFUGAL MOLD

Albert B. Hemstreet, New Hyde Park, N. Y., assignor to himself and Ernest O. Rudloff, Sr., Franklin Square, N. Y.

Application December 24, 1946, Serial No. 718,236

3 Claims. (Cl. 22—113.5)

1

This invention relates to improvements in molds of the type used in centrifugal casting machines.

An important object of this invention is to provide an automatically actuated locking mechanism by means of which the several parts from which the molds are assembled are caused to be automatically secured together during the casting operation.

A more specific object of the invention is to provide a locking means which is actuated by the centrifugal forces generated during the use of the mold in casting for locking the parts of the mold together.

Another object of this invention is to provide a heat resisting and non-conducting lining for the exposed surfaces of centrifugal molds to prevent chilling of the casting metal at the time of introduction into the mold, that is, before it fully fills all the cavities in the mold.

Other and more detailed objects of the invention will be apparent from the following description and the two embodiments thereof selected for illustration in the attached drawings.

This invention resides substantially in the combination, construction, arrangement and relative location of parts, all as will be more fully set forth hereinafter.

In the accompanying drawings:

Figure 1 is a vertical central cross-sectional view through one form of mold, illustrating the non-heat conducting lining and the locking features of the invention;

Figure 2 is a top plan view of the main body portion of the mold;

Figure 3 is a vertical central cross-sectional view through the cover portion of the mold;

Figure 4 is a vertical central cross-sectional view through another form of mold in accordance with this invention, showing three parts arranged to be locked together by centrifugal force;

Figure 5 is a vertical central cross-sectional view of the main body portion of the mold;

Figure 6 is a vertical central cross-sectional view through the central or core section of the mold; and

Figure 7 is a vertical central cross-sectional view through the cover portion of the mold.

It is a general practice today in the casting of metals, including the die casting of metals, to employ the advantages of centrifugal molding. In centrifugal molding machines provision is made for the reception of a mold having a cavity of suitable shape in a power driven chuck or spindle adapted to be rotated at high speed during casting. In such machines the mold com-

2

prises a readily insertable and removable part comprising a separate unit so that the main machine can be adapted to molding articles of various shapes by constructing suitably shaped molds for the purpose.

It is common practice to construct these molds of several parts to facilitate the introduction of inserts, cores and the like when necessary, as well as the removal of the finished casting. The common practice is to provide some form of means for locking the mold parts together when in assembled relation as, for example, by providing them with threads by means of which they can be interconnected or with some other form of manually actuated locking device.

In accordance with an important object of this invention molds of this type are so constructed that the separable parts when at rest can be assembled and taken apart without the necessity of consciously locking the parts together and unlocking them after the casting is made. In accordance with the invention, centrifugally actuated locking arrangements are provided which, of course, are normally inactive. These locking devices are so constructed that the parts can be put together and taken apart with no more effort than is required to bring them into mating relation. On the other hand, when the assembled mold is in the casting machine and revolving at the usual speeds employed in such machines, the locking devices become active to firmly secure the parts together. As soon as the machine is brought to rest at the end of a casting operation the locks are released and the mold can be easily separated. This construction greatly simplifies and speeds up the operation of the machine.

In the die casting of most metals and particularly metals which melt at high temperatures it is common practice to heat the mold to a similarly high temperature before placing it in the molding machine so that when the molten metal is introduced into it it will not freeze and thereby be prevented from fully filling all of the cavities of the mold. In order that the mold retain such high temperatures sufficiently long to complete the molding operation it is necessary to build them in relatively massive proportion. This, in turn, requires an inconveniently long period of heating in order to bring such relatively massive molds up to operating temperature.

In accordance with another important object of this invention linings for the exposed cavity surfaces into which the metal is molded are provided in the form of refractory poor heat con-

ducting materials such, for example, as compressed asbestos, carbon, graphite, and various other ceramic materials, known in the ceramic arts. As a result, molds provided with such linings can be made relatively much smaller since it is not necessary to heat them at all in most cases and very little in other cases.

Most of these objects are attained by one or both of the forms of the invention illustrated in the attached drawings.

The mold illustrated in Figures 1, 2 and 3 is of circular cross-sectional form at all points. It comprises a tapered spindle 1 adapted to be received in a chuck or tapered spindle seat in the rotatable spindle of the molding machine. One suitable form of machine with which this mold may be used is disclosed in my copending application Serial No. 718,235, filed November 3, 1947 now abandoned. Secured to the end of the spindle 1 in any suitable manner or form as an integral part thereof is a disk 2 provided with an annular recess on its upper face, formed by the peripheral flange 3. At diametrically opposed points around the circumference of the disk 2 are the bores 4 in each of which is imprisoned a steel ball 5 by swaging or pinning over the end edge of the bore a sufficient amount to retain the ball 5 therein while permitting a portion of its peripheral surface to project beyond the opening.

In the recess on the end of the plate 2 there is a lining 6 of refractory poor heat conducting material as, for example, carbon in the form of a shallow cup. This cup may be in the form of a separable insert that can be slipped into the recess in the end of the plate 2. The plate also in the form shown has a central counterbore 2' in which the centering stub 1 of a core piece 13 can be mounted. The details of construction of this core piece are not given, since they form no part of the invention by themselves and furthermore, since for each different article to be cast the core construction may be different, or no core at all may be used.

The cover for this mold comprises two cylindrical sections 8 and 9 secured together by means of threads as shown. The portion 8 is in the form of an open-ended ring while the portion 9 is in the form of a cap having an end wall. Mounted in the cap is a lining 10 likewise of refractory poor heat conducting material, such as carbon. The lining 10 comprises a separate unit having a central aperture boss 11 which extends a short distance through an opening in the end wall of the cap 9. When the parts 8 and 9 are assembled, the peripheral edge 8a forms a shoulder for locking the lining 10 in the cap. When the entire cover for the mold is in place as shown in Figure 1, the annular shoulder 8 shown in the portion 8 forms the edge of the cover to lock it in place. The inner wall of the ring 8 near its lower end is provided with an annular groove 12 which will be radially aligned with the balls 5 as shown.

The cavity C in which the metal is cast is of annular form in the particular mold illustrated. This mold is adapted to cast a rotor or a gyrocompass motor and therefore the laminations of the rotor in the form of annular rings will lie around and be positioned by the core 13 and fill the space C. These laminations have punched apertures which will be aligned when thus assembled into which the metal is molded to form the windings, all in accordance with the well known practice.

and for this reason there seems to be no need to show the laminations.

When this mold is revolved at centrifugal casting speed the balls 5 move outwardly into locking engagement with the annular groove 12 holding the cover on the mold. At this time the molten metal is poured through the opening defined by the annular boss 11 forming part of the lining 10 onto the top of the core 13 and is thrown from there by centrifugal force outwardly. The metal then works around all the unfilled areas and into the openings of the laminations, all in accordance with well known practice. Since the space C is filled with the laminations no refractory lining is needed for the annular wall defining this space but should this wall be exposed because of the shape and structure of the particular object being cast a tubular lining might likewise be provided for this wall. Of course, as soon as the casting is complete and the mold comes to rest it can be ejected from the machine and taken apart without further ado as the centrifugal lock is inactive.

A brief discussion will be given of the modification shown in Figures 4 to 7, inclusive. The purpose of this embodiment is to show the extent to which the locking feature of this invention can be carried. The mold of these figures consists of three parts locked together in use by the centrifugal lock. As before, a tapered spindle 14 is provided which in this case has a cylindrical bore therethrough. The base plate or disk 15 is attached to the spindle 14 or is integral therewith, as before, and is provided with pairs of diametrically arranged bores 16 in which the balls 17 are imprisoned as before. The disk 15 is provided with a central counterbore 18 which has an annular groove 19 in the wall thereof. The core comprises a main body portion 24 and a central stud 20 adapted to lie in the counterbore 18. Secured to the central stud 20 concentrically therewith is a shaft 23 adapted to lie in the bore of the spindle 14. This stud is provided with pairs of diametrically opposed counterbores 21 in which are imprisoned, in the manner previously described, the locking balls 22. The cover 25 is provided with an aperture extension 26 of circular cross section through which the molten metal is poured and with an annular recess 27 in the skirt near one end. The cap is counterbored to form a shoulder 28 on which the upper end of the plate 15 engages when the parts are assembled.

This mold has been designed to cast metal around a carbon ring insert CR so as to fill the space C in the mold around this insert. The ring CR is mounted on the portion 24 of the core so as to be accurately positioned by it and the core is then dropped into place so that the shaft 23 lies in the spindle 14. The cover 25 is then slipped over the base plate 15 and when this entire unit is placed in the casting machine it will be seen that the parts become locked together under the concentric force generated. In other words, the core is locked in the base plate and the cover is locked on the base plate. It is, of course, apparent that linings like those previously described could be used, if desired, in a mold of this type.

Those skilled in the art will readily appreciate that the subject matter of this invention can be embodied in many physical forms. This is particularly true in this case because the subject matter of the invention is concerned with metal molds which of course must in each in-

stance take a shape peculiar to the article to be cast. It follows therefore that I do not desire to be strictly limited to the disclosure but only as required by the appended claims.

What is claimed is:

1. In a centrifugal mold of the type described, the combination comprising a pair of substantially cylindrical telescoping parts forming a moulding cavity when assembled, each of said parts having at least one radial recess in the overlapping area of the parts, and a ball held in one of said recesses and radially moveable under centrifugal force to project partially into the recess of the other part to lock the parts together.

2. In the combination of claim 1, the recess in one of said parts comprising an internal annular recess.

3. In the combination of claim 1, a core member mounted in said moulding cavity having a portion telescoping with one of said first pair of telescoped parts, said part and said core member each having at least one radially aligned recess and a ball held in one of said recesses and radially movable into the other to lock the core 25 in place.

ALBERT B. HEMSTREET.
